F. M. GINGER

DANGER AND ROUTE INDICATOR FOR RAILWAY CARS

Filed March 9, 1926

UNITED STATES PATENT OFFICE.

FRANK M. GINGER, OF ELDORADO, KANSAS.

DANGER AND ROUTE INDICATOR FOR RAILWAY CARS.

Application filed March 9, 1926. Serial No. 93,499.

This invention relates to placarding or indicating devices for railway cars and particularly to means for indicating whether a car contains inflammable matter or other dangerous commodity and for also indicating the routing of the car, though it is to be understood that the invention is not limited to this use.

Oil tank cars must be placarded where the oil tank contains particularly inflammable matters such as gasoline, casing head gasoline or the like and all railways cars which carry powder or other inflammable or explosive material must be placarded to indicate this fact. The placarding is done either by pasting to a car a sheet of paper having proper indicia thereon or by attaching to the car a wooden board which has a relatively short life and which quite readily warps and splits. Route cards are usually either pasted or tacked upon the side of the car and it is extremely difficult to paste the route card upon the side of the car, particularly if the car is wet and there is a great liability of the routing card coming off. Tacking has the objection that the tacks must be removed whenever a new card is to be put in place and in cold weather this is very unpleasant. This must be done each trip when the tank is loaded with gasoline or any other dangerous or explosive contents.

The general object of my invention is to provide a danger indicator and route card holder which may be readily applied to ordinary freight cars or tank cars, and which may be used to readily indicate whether the car is loaded with inflammable or other dangerous matter or not.

A further object of my invention is to provide a device of this character having an indicating disk or plate permanently mounted upon it which in one position will indicate the dangerous contents of the car and in other position indicate that the car is not loaded with inflammable or explosive matter, and in this connection provide means for locking this disk and indicating plate in place.

A still further object is to provide a device of this character embodying a bracket which carries upon it a route card holder, this holder being so constructed that the route card may be readily inserted, removed or replaced at any time with ease and with rapidity and yet so constructed that the

route card will not be likely to drop out and become lost.

Other objects will appear in the course of the following description.

My invention is illustrated in the accompanying drawings wherein:

Figure 1 is a vertical sectional view through an indicator constructed in accordance with my invention;

Fig. 2 is a section on the line 2-2 of Figure 1;

Fig. 3 is a fragmentary top plan view with the lock closed;

Fig. 4 is a like view to Figure 3 but showing the lock open;

Fig. 5 is a section on the line 5-5 of Figure 2;

Referring to these drawings it will be seen that the bracket which supports my danger indicator and route card consists of a strip of metal bent to provide the horizontally disposed portion 10 having perforations through it whereby it may be readily attached to the frame of a tank car, freight car, or other car or truck, this strip being formed to provide a second horizontal portion 11, having a slot 12. Beyond this horizontal portion 11 there is formed a vertical portion 13 which at its upper end is upwardly and outwardly inclined, as at 14, this portion 14 being formed with an aperture or slot 15 having somewhat the form of a keyhole slot and embodying a circular opening intersected at its inner end by a transverse slot 15a.

Mounted upon this upwardly inclined end portion 14 is a lock consisting of a plate of metal 16, having a more or less rectangular opening 17 cut through it and formed at its upper end with an inwardly and rearwardly projecting tongue 18, which is sharp pointed. This plate 16 is formed with downwardly and inwardly bent flanges 19 which embrace the side edges of the portion 14 so that this part 16 constitutes a sliding lock urged downward and rearward by gravity.

Coacting with the bracket is an indicating plate designated generally 20, preferably though not necessarily diamond-shaped or rectangular in form, having a downwardly extending lug or tongue at its lower end adapted to slide through the slot 12 and at its upper end having an upwardly projecting tongue 22 terminating at its upper end in a circular head 23, having a diameter larger than the diameter of the open-

ing 15 or the length of the intersecting slot 15^a. This head is intended to be disposed through the opening 15 and because of its larger diameter cannot be pulled 5 backward through this opening. In order to accomplish this result the head is initially formed with a diameter smaller than the diameter of the opening 15 or the length of the slot 15^a and after being passed through 10 the opening 15 or slot 15^a, this head may be flattened out by hammering so as to increase its diameter, thus making it impossible to detach this head 23 from the portion 14 of the supporting bracket. The tongue 22 is 15 provided with a slot 24 through which the pointed lug 18 of the sliding lug 16 passes. When the lock is out of engagement with the tongue 22 it is possible to raise the indicator 20 so as to carry the tongue 21 out of 20 the slot 15 and under these circumstances the indicator may be turned entirely around so as to display its other face. One face may for instance, be painted white and the other face be painted red so that when the indicator 25 is turned with its red face outward it will indicate that the car carries dangerous material while when it is turned with its white face outward it will indicate that the contents of the car are harmless. The lock 16 30 slides freely downward upon the portion 14 so that the ordinary oscillation of the car as it passes over the track will tend to cause the downward movement of the locking slide and thus there will be no danger while the 35 car is enroute, of the locking slide being detached from the tongue 22. Thus it is necessary to manually raise the slide and manually shift or turn the indicator in order to change the indicator.

40 Attached to the portion 15 is a route card carrying plate designated generally 25. This plate is formed with a plurality of diagonally arranged slots 26 through which the corners of the route card 27 may be 45 readily inserted. This plate is engaged with the portion 13 in any suitable manner but as illustrated, the plate extends behind the portion 13 and is formed at one end with an inwardly bent tongue 28 engaging 50 over the face of the portion 13, and between the route card and the end, the plate is formed with an inwardly pressed tongue 29 which engages over the portion 13. The 55 lower edge of the plate 25 is formed with an outstanding flange 30 which extends below the horizontal portion 11 and has a rebent tongue 31 engaging over the face of the portion 11, thus locking the plate 25 to the body 10.

60 It will be seen that a route card may readily have its corners tucked into the slots 26 and then the route card will be held from any accidental detachment and from damage. It will be seen that this device is made 65 of sheet metal and, therefore, has no parts

to break, that is does away with the necessity of tacking signs upon the cars, that it requires no repairs and lasts the lifetime of the car and provides a very handy route card and consignee card holder, the rear 70 face of the card being adapted to be used for this purpose. This device permits the use of printed route cards or stenciled cards having thereon the class of oil shipped, the route and the return address.

75 While I have illustrated a form of my invention which I have found to be particularly effective in actual practice I do not wish to be limited to the details herein described as these may be varied in many ways 80 without departing from the spirit of the invention as defined in the appended claims.

75 I claim:

1. An indicator of the character described comprising a support having a lower horizontally disposed portion having a slot, and an upper portion having an opening and a slot intersecting said opening tangentially thereto, an indicator plate having a lower tongue insertible into the slot in the lower portion of the support, the upper end of the plate having an upwardly extending tongue, the tongue having a width equal to the diameter of the upper opening in the support and equal to the length of the intersecting slot, the tongue at its upper end being formed with a reduced neck and a head above the neck, the tongue at the neck having a width equal to the opening at the intersection of the slot whereby said plate 100 when lowered may have its tongue shifted into said slot and when raised will be held in said slot against rotation, and means for locking the plate in a raised position but with the lower tongue in engagement with the slot in the lower portion of said support.

105 2. An indicator of the character described comprising a support having a lower horizontally disposed portion having a slot, and an upper portion having an opening and a slot intersecting said opening tangentially thereto, an indicator plate having a lower tongue insertible into the slot in the lower portion of the support, the upper end of the plate having an upwardly extending tongue, the tongue having a width equal to the diameter of the upper opening in the support and equal to the length of the intersecting slot, the tongue at its upper end being formed with a reduced neck and a head above the neck, the tongue at the neck having a width equal to the opening at the intersection of the slot whereby said plate 110 when lowered may have its tongue shifted into said slot and when raised will be held in said slot against rotation, and gravity actuated means for locking the plate in a raised position but with the lower tongue in engagement with the slot in the lower portion of said support.

3. An indicator of the character described comprising opposed portions, one of said portions being formed with a slot and the other with an opening, an indicator plate disposed between said portions and having tongues, one insertible through and fitting said slot and the other extending up through said opening and being rotatable therein when the first named tongue is disengaged
- 5 10 15 20 25 30 35 40 45 50
- from the slot by lifting movement, said indicator plate being rotatable to thereby display either side of the indicator plate and vertically movable to engage or disengage said first named tongue from the slot, and means for locking the indicator plate from vertical movement to thereby hold the first named tongue in engagement with said slot.
4. An indicator of the character described comprising a bracket having a horizontally disposed supporting portion formed with a slot, one end of the bracket having an upwardly inclined portion formed with an opening, an indicator plate disposed between said portions and having tongues, one insertible through said slot and the other extending up through said opening, said indicator plate being rotatably shiftable to thereby display either side of the indicator plate, and means for locking the indicator plate from rotative movement comprising a slide mounted upon the second portion of the bracket, the slide having an opening through which the tongue of the indicator plate extends and being provided with a lug, the tongue of the indicator plate having a slot with which said lug is adapted to engage.
5. An indicator of the character described comprising a bracket having a horizontal transversely slotted portion, and an upwardly inclined portion having an opening, an indicator plate having a downwardly extending tongue normally disposed through said slot and having an upwardly extending tongue normally disposed through said opening, the last named tongue having a head larger in diameter than the opening and the tongue being provided with a transverse slot, and a lock for the indicator comprising a slide mounted upon the upwardly inclined portion of the bracket and having
- an opening through which the tongue projects, one wall of the opening having a lug insertible through the slot in the tongue, the inclination of the bracket causing said 55 slide to shift in a direction to carry the lug through the slot in the tongue.
6. An indicator of the character described comprising a support having a vertical portion, and upper and lower portions extending at an angle to the vertical portion, one of said portions having a slot and the other portion having an opening, said last named portion being inclined, an indicator plate having a tongue at one end insertible into 60 65 70 75 80 85 90 95
- and fitting the slot and a tongue at the other end insertible into said opening, said last named tongue being slotted and said plate being vertically movable with relation to the support to thereby engage or disengage the first named tongue from the slot in the support and a lock slidable on the inclined portion of the bracket and having a tongue insertible into said slot in said tongue to thereby lock the indicator plate from vertical movement and rotation.
7. An indicator of the character described comprising a support having a horizontally disposed portion formed with a slot, an opposed portion having an opening, and a 80 slot intersecting said opening, an indicator plate having a tongue insertible into the first named slot, the other end of the plate having a tongue of a width equal to the diameter of the second named opening and 85 equal to the length of the intersecting slot, the tongue at its end being formed with a reduced neck and a head beyond the neck, the tongue at the neck having a width equal to the opening at the intersection of the slot, 90 whereby said indicator plate when vertically shifted in one direction may have its second named tongue shifted into said slot and when shifted vertically in the other direction will be held in said slot against rotation, 95 and means for locking the plate in said last named position and with the first named tongue in engagement with the first named slot.

In testimony whereof I hereunto affix my 100 signature.

FRANK M. GINGER.
